TELEVISION APPARATUS

Arno Zillger, Narberth, Pa., assignor to National Television Corporation, Wilmington, Del., a corporation of Delaware

Application December 23, 1933, Serial No. 703,790
Renewed December 19, 1939

10 Claims. (Cl. 178—5.8)

This invention relates to television apparatus and particularly to a machine for translating the picture and sound on a motion picture film into electrical impulses.

5 One of the objects of the invention is to provide a simple and effective machine for this purpose.

Another object of the invention is to provide a 10 picture and sound translating machine which will pick-up both the picture and sound with a minimum of distortion.

Another object of the invention is to provide a 15 novel and highly efficient picture scanning device.

Another object of the invention is to provide a 20 picture and sound motion picture apparatus in which the film is moved through both the picture and sound reproducing devices by a single driving means.

25 Another object of the invention is to provide a simple framing device for a motion picture scanner.

Other objects of the invention and objects relating particularly to the construction and assembly of the various parts will be apparent as the description proceeds.

The invention is illustrated in the accompanying drawings in which:

Fig. 1 is a side elevational view of a machine 30 embodying the invention;

Fig. 2 is an enlarged side elevational view of the mid-portion of the machine with the doors open or removed;

Fig. 3 is a plan view of a portion of the machine with the upper casting removed, the view being taken on the line 3—3 of Fig. 2;

Fig. 4 is a plan view of a portion of the machine showing the principle of the picture scanning device;

Fig. 5 is a rear sectional view of the machine taken on the line 5—5 of Fig. 2;

Fig. 6 is a front view partly in section of the film controlling mechanism for the picture scanning device taken on the line 6—6 of Fig. 2;

Fig. 7 is a rear sectional elevational view of the machine taken on the line 7—7 of Fig. 2 and showing the film steadyng mechanism;

Fig. 8 is a side elevational view of a portion of the machine taken on the line 8—8 of Fig. 7;

Fig. 9 is an enlarged sectional rear view taken on the line 9—9 of Fig. 2 and showing the sound reproducing mechanism;

Fig. 10 is a side elevational view of the film drum supporting and adjusting mechanism taken 55 on the line 10—10 of Fig. 9;

Fig. 11 is an enlarged rear sectional view of the film scanning mechanism taken on the line 11—11 of Fig. 2;

Fig. 12 is a fragmentary plan view of the film scanning mirror wheel;

Fig. 13 is a perspective view of one of the tiny mirrors used in the mirror wheel;

Fig. 14 is a fragmentary sectional view through the rim of the mirror wheel taken on the line 14—14 of Fig. 12;

Fig. 15 is a sectional elevational view of the light source and optical system for the film scanning device;

Fig. 16 is a diagrammatical view of a modified arrangement of the light cell and associated 15 apparatus;

Fig. 17 is a diagrammatical view of the parts of a modified form of scanning system;

Fig. 18 is a diagrammatical view of still another form of scanning system;

Fig. 19 is a vertical sectional view of a horizontal framing device for the machine; and

Fig. 20 is a diagrammatical elevational view of a machine equipped with separate driving motors for the various parts.

Broadly the invention comprises a means to scan a motion picture film in successive lines and to take the sound from the sound track thereof as the film moves at a steady continuous rate through the machine. The scanning is accomplished by projecting light rays through a very thin line of the film and redirecting the rays by the system of moving mirrors into a light-sensitive cell. The sound is picked up in the usual manner by directing the light through the film in a thin line and causing such light to fall upon another light-sensitive cell.

One manner of scanning the film which may be the preferred form is illustrated in Fig. 4 in which the film 10 is moved continuously past a thin slot 11 which extends transversely of the film and has a width corresponding to the width of one of the scanning lines. Parallel light rays indicated at 12 pass through the film and slot 11 and are intercepted by tiny mirrors 13 which are mounted on a wheel 14. The mirrors are spaced apart sufficiently so that one mirror at a time will pass through the rays of light coming through the slot 11. The mirrors 13 redirect the light rays, which assume a density corresponding to the density of the film through which they pass, to the lens 15 which in turn concentrates the rays upon the light-sensitive element 16 of a light-sensitive cell 17. When one mirror has cut through the strip of light and passes

55

out at the far side another mirror is ready to cut it a second time, but by this time the film is moved downwardly a distance equal to the width of one line of the film and hence the second mirror scans the second line. This process is continued until one picture on the film has been completely scanned whereupon the same thing occurs with respect to the successive pictures. After passing the slot where the picture is scanned the film passes through mechanism to be herein-after described for reproducing the sound from the sound track.

Referring to Fig. 1 of the drawings the machine comprises a base casting 18 having legs 19 provided preferably with cushioned feet 20 and made adjustable in length by means of a split sleeve 21 attached to the base 18 and in which the leg 19 is slidable. The casting 18 extends upwardly with a central web member 20a and a forwardly extending arm 20 and is provided with a flat plate 21 on the top thereof forming a support for the other parts of the machine.

The main casting 22 rests upon the plate 21 and contains the sound reproducing mechanism as well as the driving shafts for the moving parts of the machine. The casting 22 comprises a box-like structure somewhat rectangular in shape and provided with a flattened upper edge 23 upon which rests the upper casting members 24 and 24a. The casting member 24 supports the film scanning wheel 14 and acts as a cover for the forward part of the gear box while the casting member 24a is a box-like structure carrying the light source, and various optical systems. This casting is also provided with a flattened upper edge 25 upon which rests the upper casting 26 carrying the upper film reel.

Referring now more specifically to the main casting 22 this comprises several compartments for housing various parts of the apparatus. As viewed in the plan view of Fig. 3 a light compartment 27 is situated at the lower left hand corner of the figure and is adapted to house the exciter lamp 28 for the sound reproduction. A wall 29 separates this compartment from the film drum compartment 30 through which the film passes and in which is positioned the light-sensitive cell 31 for picking up the sound. Still farther forward of this compartment and separated from it by the wall 32 is the gear compartment 33 which extends clear across the front or right end of the casting and rearwardly on the far side of the sound compartment 30 and the light compartment 27, these compartments being respectively separated therefrom by means of walls 34 and 35. Still another compartment 36 is provided in the forward end of the casting, toward the observer looking at Figs. 1, 2 and 3, formed by an extension 34 of the casting provided with an open slanting face 35a upon which may be attached a plate 36 for holding various electric devices such as switches for controlling the apparatus.

Another extension 37 is attached to the plate 21 on the base casting and also to the main casting 22 and forms the base for an electric motor 38 which is preferably of the synchronous type and in the present instance adapted to run at a speed of 1800 revolutions per minute on 60 cycle alternating current. As shown the motor shaft 39 is provided with a fibre gear 40 on the end thereof which meshes with an internal gear 41 provided on a circular plate 42 attached to a shaft 43 (Fig. 3). A suitable guard 44 may be provided around the gear connection as shown.

The shaft 43 is mounted in ball bearings 45 and 46, the first secured in the front wall of the casting 22 and the second mounted just forward of the wall 32 forming the rear wall of that portion of the gear box. A suitable packing ring 47 is provided to prevent any oil which may be in the compartment 33 from passing out along the shaft 43.

A pinion gear 48 attached to the shaft 43 at about its midpoint meshes with a larger gear 49 mounted on an auxiliary driving shaft 50 which is mounted in the gear box between a ball race 51 near the front wall and a second ball race 52 mounted near the rear end of the casting just beyond the exciter lamp compartment.

A spiral gear 53 is also mounted on the shaft 43 at a point near the inner end thereof and this gear meshes with a second spiral gear 54 mounted on a vertical spindle 55. The spindle 55 is mounted in the upper casting 24 and has its lower end mounted in a ball race 56 attached to a downwardly extending member 57 formed integral with the casting 24, while the upper end is mounted in a ball race 57a held in the upper face of the casting 24. The spindle 55 supports the mirror wheel 14.

The shaft 50 is made a trifle larger in diameter than the shaft 43 adjacent the gear 49 but tapers down to a smaller cross sectional diameter towards the rear portion thereof. At a little less than half way to the rear of the shaft 50 is mounted a spiral gear 58 which meshes with a larger spiral gear 59 keyed upon a sleeve 60 and held thereon by a second external sleeve 61.

The sleeve 60 is rotatably mounted upon an inner sleeve 63 which extends completely through the gear compartment and is rigidly secured by means of bolts 64 passing through a flange 65 on the inner end of the sleeve and securing it to the wall member 34 through which it passes. The outer ends of the sleeves 60 and 61 pass through a hole 66 in the wall 67 of the casting and a suitable packing ring 68 is provided for preventing any leakage of oil. The sleeves 60 and 61 extend slightly beyond the packing ring 68, the sleeve 60 being slightly longer than the sleeve 61, and upon the end of the sleeve 60 is positioned a disc 69, secured to the sleeve and provided with a plurality of pins 70 extending a short distance therefrom.

Inside of the bearing sleeve 63 I provide a shaft 71 which is rotatably mounted in the sleeve and has a plate 72 of about the same diameter as the plate 69 mounted upon the end thereof. The plate 72 is provided with an extended sleeve 73 or hub 73 which is rigidly secured to the shaft 71 by means of the pin 74. The end of the sleeve 63 extends outwardly beyond the wall 67 and also beyond the end of the sleeve 60 which supports the plate 69, this latter distance being sufficient to provide space between the plate 69 and the plate 72 for shock absorbing springs 75. The sleeve 60 is provided at its inner end with a shoulder 76 against which the gear 59 abuts and this gear is held in place by the sleeve 61 which is in turn held by the plate 69 at its opposite end. The sleeve 63 is also provided with a shoulder 77 against which the inner end of the sleeve 60 abuts and the sleeve 60 is held in place by means of a washer 78 secured by a ring 79 fastened to the sleeve 63 by means of a spring clip 80 which extends into a recess in the sleeve as shown clearly in Figs. 7 and 8.

A plurality of pins 81 are mounted on the plate 72 and extend inwardly spaced from the center

the same distance that the pins 70 are spaced. The springs 75 connect the pins 81 with the pins 70, as clearly shown in Fig. 8, so that the plate 72 is driven from the plate 69 through the 5 resilient springs 75. The fly wheel 82 is bolted by the stud bolts 83 to the plate 72 and is provided with an inwardly extending rim 84 which covers the plates 72 and 69 although of course being spaced from the latter to permit free relative movement therebetween. A guard 82a may be provided surrounding the fly wheel.

From this construction it will be seen that the gear 59, being driven from the spiral gear 58 and shaft 50, rotates the plate 69 through the sleeves 15 60 and 61 and thereby drives the plate 72 and fly wheel 82 through the resiliency of the springs 75. Inasmuch as the fly wheel and plate 72 are attached to the shaft 71 the shaft is also rotated by the fly wheel which in turn rotates a film 20 sprocket 85 which is mounted upon the inner end thereof. The sprocket 85 is so positioned on the shaft that it aligns itself with the strip of film 10 which it draws through the machine. The shaft 71 is prevented from moving outwardly 25 with respect to the sleeve 63 by a smaller sleeve 86 which is pinned to the shaft adjacent the sprocket.

In the same compartment 30 for the sound reproduction I provide a drum 90 at the center 30 of which is mounted the light-sensitive cell 31 and around which the film is drawn when the sound is taken from the sound track thereof. An enlarged section of this drum is shown in Fig. 9.

35 This drum is provided with a rim 91 having the outer portion 92 of slightly less diameter than the inner portion 93. The portion 92 is just long enough to permit the film 10 to lie snugly around it with the sound track 94 thereof extending outwardly over the edge of the drum thus permitting light to be projected through the sound track without interfering with the drum. The portion 92 is also made with a slight taper, being larger in diameter at the inner shoulder 40 than it is at the outer edge, thus imparting to the film a tendency to lie snugly against the shoulder as it passes around the drum in the same manner that a belt rides to the point of largest diameter on the pulley. The rim 91 is provided preferably 45 with a taper 95 on the inner edge of the rim adjacent the side over which the film extends so that the edge of the drum is relatively thin where it contacts with the film.

The drum is provided with an inwardly extending web 96 at about the center of the rim which is formed integral with a sleeve 97 extending slightly beyond the inner edge of the drum. This sleeve is mounted for rotation in a bearing sleeve 98 the outer end of which bears against one 50 side of the web 96 thus limiting the movement of the sleeve 97 into the sleeve 98. The sleeve 98 is provided with a conically tapered portion 99 which terminates in a supporting sleeve 100 which is adapted to snugly fit into a tubular opening 55 101 formed in an outwardly extended portion 102 of the casting member 22. An inner wall 22a separates the opening 101 from the interior of the gear box.

A slightly reduced portion 103 of the sleeve 100 70 is threaded into a tapped portion 104 of the hole 101 so that the sleeve 100 may be screwed into position in the hole 101 and its axial position in the sound reproducing compartment may, therefore, be determined by the rotation of the sleeve 100 75 in the tapped hole.

In order to lock the sleeve 100 in a desired position in the casting wall 102 I provide a plurality of laterally extending grooves 105 in the extreme end of the sleeve 100, one of which is adapted to be engaged by a lug 106 extending from the inner edge of a washer 107 adapted to slip over the end of the sleeve 100. The washer is prevented from turning by means of a screw 108 which passes through a hole 109 in a lug 110 extending from the outer edge of the washer 107 and is threaded 10 into a tapped hole 109a in the extension 102. An additional hole 111 may be provided in the lug 110, spaced from the hole 109 a distance equal to one-half the distance between two of the grooves 105, so that not only is it possible to rotate 15 the sleeve 100 in stepped position depending on the spacing of the grooves 105 but the distance between these stepped positions may be halved by shifting the screw from the hole 109 to the hole 111. By this construction it is possible 20 to get a very delicate adjustment with respect to the axial positioning of the drum in the sound reproducing compartment.

In order to hold the drum in position in the sleeve 98 and also to support the light-sensitive 25 cell 31 I provide another sleeve 112 whose outer diameter is slightly smaller than the inner diameter of the drum sleeve 97. This sleeve fits inside of the sleeve 97 and is provided with a rim 113 on its outer end which is somewhat larger 30 in diameter and the inner face of which is adapted to contact with the outer side of the drum web 96. The rim 113 thus holds the drum in position at the same time permitting rotation 35 thereof.

The sleeve 112 similarly to the sleeve 98 is provided with a conical portion 114 which conforms to the conical portion 99 of the sleeve 98 and is spaced slightly from it. A long sleeve 115 is formed integral with the conical portion and terminates flush with the end of the sleeve 100. The sleeve 115 fits snugly within the sleeve 100 so that it may be merely pushed into position with the desired frictional contact against the web 96 of the drum 90, and it may be held in position 40 by means of cap screws 116 threaded radially into holes 117 provided in the end of the sleeve 100, there being a reduced portion 118 in the end of the sleeve 115 to receive the ends of the screws. By loosening the screws relative movement 45 between the sleeves 115 and 100 may be had so that the position of the sleeves with respect to each other may be changed both rotatably and axially.

Within the sleeve 112 I provide a socket 119 for 50 the photo-electric cell 31. This socket 119 may be similar to any standard socket for a two terminal electron device and is shown in this instance as comprising an insert 120 of Bakelite or other insulating material fitted securely into the 55 sleeve 112 in which is embedded spring clips 121 and 122 for contacting with the terminals 123 and 124 respectively of the photo-electric cell 31.

For making the connections to the cell I have conveniently used a single insulated wire 125 60 provided with a wire mesh shield 126 and have connected the shield to the spring clip 122 which connects in this case to the negative terminal of the cell, while the wire proper 125 connects to the clip 121 which is connected to the anode terminal 65 123 of the cell. The rotatable adjustment of the sleeve 115 permits the rotatable adjustment of the cell. A metal shield 127 having a suitable opening 127a in one side thereof to permit the entrance 70 of the modulated light may be positioned with 75

frictional engagement within the sleeve 113 and held against rotation by a pin 128 mounted in a rim 129 on the shield.

The exciter lamp 28 is mounted within the compartment 27 in a socket 130 which may be supported in an adjustable bracket 131 which is so arranged that the lamp may be raised or lowered or moved axially.

The compartment 27 is provided with a door 140 preferably hinged at the top at 141 and provided at the bottom with a knurled headed screw 141a for locking the door in closed position. The door may have an ammeter 142 mounted thereon which may be suitably connected in series with the exciter lamp so that the current flowing therein may at all times be ascertained.

In the wall 29 between the exciter lamp compartment and the sound compartment 30 is provided an opening 143 in which is positioned the optical system 144. This optical system may be similar to that used for sound-on-film reproduction and is thought not necessary to describe here. The function of the optical system is of course to concentrate the light from the exciter lamp through a very fine line 145 in the film sound track on to the light-sensitive cell. The optical system may be supported on a suitable bracket 146 which is provided with means to permit focusing of the optical system by means of the screws 147.

The film enters the sound reproducing compartment from an opening 150 in the top and passes over the drum 90 in a counterclockwise direction coming up to a point even with the center line of the drum and then passing over the sprocket 85 in a clockwise direction and then out through an opening 151 in the bottom of the casting where it is wound upon a reel in a manner to be hereinafter described. In order to hold the film on the sprocket 85 I provide an auxiliary roller 152 which is adapted to contact with the film at the upper side of the sprocket 85 and is gently urged against it. To permit this pressure and also to permit removing of the roller 152 for inserting the film, the roller is rotatably mounted upon an arm 153 which is pivoted upon a pin 154 threaded into the wall of the casting. The spring 155 anchored to a lug 156 on the front wall 32 bears against the bracket 153 so as to urge it in a counterclockwise direction which presses the roller against the sprocket. The spring 155 is so positioned that the bracket may be moved manually away from the sprocket whereby the end of the spring will pass over the corner of the bracket and hold it in its separated position.

I also provide a guard 157 underneath the sprocket formed of a piece of sheet metal and having an edge 158 which is positioned closely adjacent to the sprocket at the point where the film leaves it so that in case the film sticks to the sprocket it cannot be drawn around it.

A door 159 may be provided for the sound reproducing compartment so that the compartment is completely closed when in operation to exclude dust and light. As shown a boss 160 is provided on the upper right hand corner to provide an integral cavity for housing the outer end of the pivoting screw 154. The door is preferably hinged at the left side by the hinge 161 and a locking knob 162 may be turned to lock it in its closed position.

The upper casting 24 contains the forward compartment 163 which forms a cover for the gears in the gear box compartment 33 of the lower casting 22. The rear upper casting 24a

forms a cover plate for a portion of the gear box in the lower casting and is separated by the wall 164 into two rear compartments 165, to accommodate additional driving parts, and 166 through which compartment the film passes and is suitably illuminated.

An auxiliary shaft 167 is vertically mounted for rotation in suitable bearings 168 and 169 at the top and bottom of the casting just below which the lower end of the shaft protrudes.

A spiral gear 170 is keyed to the lower end of the shaft. The gear 170 meshes with the small spiral gear 171 mounted on the shaft 50 adjacent the rear end thereof, and the shaft 167 is thus driven from the shaft 50. At the top of the shaft 167 and above the bearing 168 is positioned a worm wheel 172 which meshes with a worm 173 attached to a shaft 174 mounted at right angles to the shaft 167 for rotation in a bearing member 175 secured in an opening in the wall 164. A sprocket 176 is attached to the end of the shaft 174 and is, therefore, positioned in the compartment 166 and serves as a drive to pull the film 18 so as to unwind it from its reel 177 which is supported for substantially free rotation in the upper reel housing 178 mounted on top of the casting 24a. The reel housing is supported upon the cover plate 26 which is suitably bolted to the casting 24a and which is provided with a slot 180 through which the film may be drawn into the compartment 166.

An idler roller 181 is mounted just forward of the sprocket 176 and the film passes downwardly in a clockwise direction over this roller before it rides over the sprocket in a counterclockwise direction. The film is held on the sprocket 176 by means of a roller 182 mounted on a pivoted bracket 183 which is urged towards the sprocket by means of a spring 184 mounted on a bracket 185.

The film then passes over an auxiliary roller 186 which is rotatably mounted in a suitable film guide 187 which guides the film past the forward opening slot 11 formed in a plate 188 attached to the front wall of the casting and shown best in Fig. 6. The film guide 187 may be similar to a guide used in an ordinary picture projector being hinged at the far side so that it may be opened for the insertion of the film and being provided with a catch 188 for locking it in its closed position.

Another auxiliary roller 189 is positioned below the film guide 187 and is rotatably mounted by means of a pin 190 upon a vertically movable member 191 being guided in its vertical movement by a portion 192 of the casting on one side and the edges of two plates 193 and 194 on the other side. An arm 195 is attached to the member 191 and extends vertically upward its upper end being provided with rack teeth 196. A spindle 197 provided with a manually operable arm 198 extending at right angles thereto is rotatably mounted in bearing members 199 and 200 on the front of the casting 24a above the casting 24 and also above the slot plates 188 and has its end provided with gear teeth 201 which mesh with the rack teeth 196 to raise and lower the arm 195 when the spindle 197 is rotated. Raising or lowering the arm 195 raises or lowers the roller 189 thus raising or lowering the relative position 70 of the film with respect to the slot 11. This frames the picture.

In order to permit the relative movement of the film in this manner and also to allow for shrinkage or expansion of the film between the 75

driving sprocket 85 and the driving sprocket 176 I provide the film with a loop 202 between the sprocket 176 and the roller 186. This loop becomes larger when the roller 189 is moved upwardly and smaller when it is moved downwardly.

The casting 24a has an extended portion 203 just in front of the roller 189 forming a compartment 204 in which is mounted an idler roller 205 shown in Figs. 2 and 9. This roller is mounted on a pin 206 which is threaded into a boss 207 formed in the wall of the casting. The film passes under the framing roller 189 which turns in a counterclockwise direction and up and over the roller 205 in a clockwise direction passing downwardly through the opening 150 in the top wall of the casting 22 directly into the sound compartment 30 where it passes over the drum 90 in a manner already described.

The mirror wheel 14 for scanning the picture lines is mounted on the upper end of the shaft 55. The shaft extends upwardly through an opening 208 in the top of the casting 24 in which opening the ball race 57a is supported. A dish-shaped housing member 209 is secured by stud bolts 210 to the casting 24 and has an opening 211 to permit the passage of the shaft therethrough and to also receive a packing ring 212 for preventing leakage of oil out of the casting 24. The packing ring 212 is suitably held by bolts 213 which, together with the bolts 210, may be locked against turning by the wires 214.

The mirror wheel 14 comprises a disc having a hub member 215 which is keyed to the end of the shaft and held thereon by a suitable nut 216. The tapered web portion 217 extends outwardly terminating in a rim 218 provided with upper and lower circular grooves 219 and 220. The rim 218 is also provided with a plurality of slots 221 which extend completely through the rim parallel to the axis of the wheel but having an angular relation to radial lines through the wheel. Each slot has the same angle with respect to a radial line drawn through its intersection with the outer circumference of the rim as all of the other slots.

The mirrors are formed of a plurality of strips 222 of stainless steel or other suitable material which have narrow central portions 223, equal in width to the thickness of the rim 218 between the two grooves, while its ends 224 and 225 may be any suitable width but are shown in the present construction as being equal in width to the thickness of the rim 218. The tip end 226 of the portion 225 is ground and polished to form an accurate mirror with high reflecting characteristics. These strips 222 are inserted in the slots 221 and are locked in position by means of two rings 227 and 228 which fit into the grooves 219 and 220 respectively and are held securely thereto by means of screws 229 which pass through countersunk holes provided for them in the ring 227 and through holes 230 in the rim 218 and are threaded into tapped holes provided for them in the lower ring 228.

The dish-shaped cover plate 231 may be positioned over the mirror wheel 14 and is adapted to fit the outer circumference of the housing member 209 and may be secured thereto by suitable bolts 232, (Fig. 2). Both of the housing members 209 and 231 may be provided with openings 233 through which the light from the slot 11 may pass to the mirrors and out again to the light-sensitive cell 17.

The winding reel housing 234 is mounted on the lower casting and contains a rotatable shaft 235 which is mounted in a suitable bearing and

extends through to the opposite side of the machine where it is provided with a slip pulley 236 which is in turn rotated by a belt 237 (see Figs. 1, 5 and 8). The belt 237 passes over the second pulley 238 rotatably mounted on a smaller shaft 239 which is rotatably mounted in a recessed portion 240 of the casting 22. The shaft 239 is mounted in two bearings 241 and 242 mounted respectively in the wall of the casting and in a separate bracket member 243 attached to the wall. A spiral gear 244 is keyed on the shaft 239 between the two bearings and meshes with a spiral gear 245 (Fig. 3), keyed to the shaft 56.

Rotation of the shaft 56 rotates the pulley 238 through the spiral gears 245 and 244 and thus drives the winding reel by means of the belt 237. The slip of the winding reel is permitted to allow for the change in speed as the film winds up and for this purpose the usual slip clutch 246 may form part of the pulley 236.

The casting 24 containing the gears for the machine is preferably filled with grease. Thus the bearings 45 and 46 for the main shaft and the bearings 51 and 52 for the long auxiliary shaft 56 as well as the gears connected to these shafts work in grease which also tends to lubricate the bearings of the vertical shaft 167. The upper bearing of the shaft 55 may be independently lubricated through a short pipe 247 which communicates with a duct 248 leading into a space 30 adjacent the bearing. The shaft 174 carrying the upper driving sprocket 176 may be lubricated through an oil hole 249 which may be reached through an opening 250 immediately above it.

It will be noted that the bearing sleeve 63 for the flywheel mechanism extends from the sound compartment 30 through the gear box compartment 33 and out the opposite side of the casting. A hole 251 in the outer sleeve 61 communicates with a hole 252 in the sleeve 63 so that lubricant can reach the bearing surface between the sleeve 60 and the main bearing sleeve 63. Suitable oil rings 63a on the main bearing sleeve 63 carry the lubricant in both directions and a hole 253 in the sleeve 63 permits it to reach the bearing surface between the shaft 71 and the bearing sleeve 63. Internal oil grooves 63a on the sleeve 63 insure lubrication of the shaft. The sleeve 61 may also be provided with an oil throwing ring 62 which prevents oil from passing through the opening 66.

In a similar manner the bearings for the sound drum are lubricated. A hole 254 in the sleeve 102a which extends from the inner to the outer wall of the casting permits lubricant to drop into a duct 255 in the sleeve 100 which circles the sleeve and communicates through a hole 256 to the space 257 between the sleeve 103 and the sleeve 115 and between the conical portions 99 and 114. The lubricant flows through this space to the inner bearing surface of the sleeve 98. It also flows inside of the sleeve 97 of the drum 90 to the outer bearing surface of the web 96 so that all the bearing surfaces of the drum are lubricated. Other moving parts of the apparatus may be oiled with lighter machine oil if found desirable.

One means by which the mirror wheel is made to pick up the successive elements of the picture line and send them to the light cell is by providing parallel rays as indicated at Fig. 4 to project through the slot 11. One means of producing these parallel rays is illustrated in Fig. 15. Here a light source 258, which may be any suitable projecting lamp such as an incandescent lamp or an arc lamp, is provided with a reflector 259 and a condensing lens 260 which condenses all of the light down to just cover a tiny aperture 261 in a

metal plate 262. An objective 263 on the opposite side of the plate parallelizes all of the rays from the aperture 261 and directs them towards the slot 11 already referred to. A cylindrical lens 264 is positioned between the optical system 263 and the slot 11 and converges all of the rays vertically but not horizontally so that they pass through the slot 11 maintaining their vertical planes. Therefore, while the rays may spread in a vertical direction on the other side of the slot there is no horizontal spreading so that as the mirror sweeps across in front of the slot it intercepts the light passing through one point of the film at a time.

The spreading of the rays vertically through the slot has an advantage in that the height of the mirrors on the mirror wheel may be greater than the width of the slot and more light can therefore be reflected to the cell.

In order to support the optical system in the machine I provide a tubular casting 265 which has a flange 266 for bolting upon the rear end of the casting 24a as with the bolts 266a. This tubular casting is slightly tapered to receive the tubular end 267 of a lamp housing 268 in which the lamp 258 is positioned. The casting 265 is provided with a plate 269 which covers its inner opening and has a hole 270 in which the optical system 263 may be positioned. A split flange 272 integral with the plate 269 permits securing the optical system 263 by tightening the bolt 273. The optical system 263 may comprise the usual cylinder 274 with a double convex lens 275 mounted in each end.

At about the center of the casting 265 I provide a shoulder 278 formed in the interior wall of the casting against which may be secured the aperture plate 262 by the screws 279. The optical system 263 is so adjusted to project the light from the aperture 261 in parallel rays towards the slot 11.

In order to converge the parallel rays to just cover the slot 11 in the front of the machine, and thereby save light which would be otherwise wasted, I provide a cylindrical lens 264 which may be mounted in a metal bracket 281 provided for that purpose. This bracket comprises a member 282 adapted to fit over the end of the optical system 274 and a lens securing member 283 which may be urged towards the member 282 by the screws 284 thus holding the lens securely in position.

The end of the casting 265 may be provided with a split cylindrical member 285 which may be tightened against the housing extension 267 by means of the bolt 286.

The concentrating lens 260 may be mounted in a tubular sleeve 288 which fits inside of the lamp extension 267 and this lens picks up the light coming from the lamp 258 and the reflector 259 and concentrates it on the aperture 261 on the plate 262.

The construction shown permits adjusting the lens 260 with respect to the lamp and the whole lamp housing with respect to the aperture plate 262 so that a proper focus of the light upon the aperture may be had. It also permits the adjustment of the optical system 263 with respect to the aperture so that the rays from the lamp are parallelized as they pass through the film slot.

In order to see where the light is properly focused on the aperture 261 I preferably provide a small window 289 of red glass cemented in an opening 290 provided for that purpose in the upper wall of the casting 265, so that the aperture in the plate 262 may be readily seen by the operator.

The lens 15, (see Fig. 4), which may preferably be a cylindrical lens is mounted in a suitable bracket 291 on the upper surface of the forwardly extending portion of the casting 24a in the proper position to pick up the rays from the mirrors, screws 292 being used for that purpose.

An amplifier 293 may be mounted on an entirely independent support (not shown) and may contain the light-sensitive cell 17 so mounted at the focus of the lens 15 that it receives the light therefrom. Thus there is no physical connection between the film scanning machine and the amplifier so that the amplifier may be suitably cushioned to eliminate any possible vibration of the machine from effecting the tubes thereof.

In making the electrical connections to the apparatus I provide a main switch box 294 mounted on the frame to which the alternating current line is connected. This box is connected by suitable cable to the motor switch 295 in the plate 36 and to the motor 38. A second switch 296 also mounted in the plate 36 may serve for the projection lamp which is preferably operated by direct current in order to insure a steady even light.

The exciter lamp for the sound is also preferably lighted by direct current and may have its own switch box 297 equipped with a switch 298 and rheostat control 299.

With the machine set up as already described a film reel may be inserted in the upper film housing 178 and the film threaded down through the slot 180, under the auxiliary roller 181 in a clockwise direction, up over the driving roller 176 in a counterclockwise direction, and down again, forming the loop 202 before it passes over the roller 186 and through the film guide 187 past the slot 11. The film may then be threaded under the framing roller 189 in a counterclockwise direction, over the idler wheel 205 in a clockwise direction, down through the opening 150, over the sound drum 90 in a counterclockwise direction, up over the drive roller 85 in a clockwise direction, down through the opening 151, and into the lower reel housing 234 where it may be wound on the reel 235a provided for that purpose.

To start the machine functioning the switch 296 is turned on thus energizing the light 258. The exciting lamp 28 is also energized by the switch 298 and the amplifier 293 is turned on as is also the sound amplifier which has not been shown but which is connected to the output of the light-sensitive cell 31. The motor 38 may then be started by means of the switch 295 and the machine starts to operate. Both driving sprockets 176 and 85 start to rotate so that the film is drawn through the machine. Inasmuch as the loop 202 is immediately underneath the upper driving sprocket 176 this sprocket serves only to draw the film out of the upper magazine thus unwinding it from the reel. The lower driving sprocket 85 alone draws the film not only over the sound drum 90 but through the film guide 187. Inasmuch as the sprocket 85 is driven indirectly of the motor by means of the flywheel 82 the film is pulled at a very constant speed, any irregularities in the action of the gears being ironed out by the inertia of the flywheel. This insures perfect sound reproduction and maintains a steady speed of the film past the slot where the picture is scanned.

As the film passes the slot 11 the parallel light rays from the lamp 258 and associated optical

systems project one line of the picture towards the mirror wheel 14 and one of the small mirrors 226 crosses the line of projection therefore reflecting that line point by point from left to right through the lens 15 to the image photo cell 17. The photo cell 17 has its characteristics varied by the changes in light intensity from left to right of this picture line and accordingly influences the amplifier causing a succession of electrical impulses corresponding to the intensity of the picture line to be sent out either by wire or radio to any television receiver which may be arranged to pick up the signal. When the first line has been scanned as just described the second mirror comes into position at the left side of the slot and sweeps across the projected beam while at the same time the film is moving downwardly and thus the second line of the picture is scanned. This process continues as the film continues to move downwardly at a continuous rate and the mirror wheel continues to move uniformly. Inasmuch as the film is moving at a continuous speed through the machine the slot 11 should be inclined downwardly slightly to the right as viewed in Fig. 6. If this inclination is correct the right hand end of the first line will just arrive at the slot as the mirror reaches that portion thereof. At this time a second line is just coming into alignment with the left hand end of the slot for the second mirror to pick up. It will be understood that the gearing is so designed as to cause this accurate relative movement of the parts.

While the number of lines scanned per picture on the film may be more or less arbitrarily chosen I have designed the machine shown and described to scan 60 lines. The mirror wheel 14 contains 30 mirrors and hence must necessarily rotate twice for the complete scanning of one complete picture. The various gear ratios in the driving mechanism are, therefore, so arranged that the mirror wheel makes two complete rotations while the film is moving through a distance equal to that from the top of one picture to the top of the next succeeding picture. It is obvious that by changing the gear ratios any number of lines per picture may be scanned by the mirror wheel.

As the film passes around the sound drum 90 in the sound reproducing compartment 30 it intercepts a very fine beam of light from the exciter lamp 28. This beam passing through the sound track on the film in a manner well known in the art affects the light-sensitive cell 31 which in turn controls the sound amplifier and reproduces the sound accompanying the picture. The length of the film between the picture slot 11 and the point on the drum from which the sound is taken is equal to the 14 inches usually separating the picture and sound accompaniment on a standard film so that the machine is adapted to use standard film.

Inasmuch as the speed of a standard film to get correct sound is at the rate of twenty-four pictures per second the machine must be run at that rate if standard sound film is to be used. Considerable television experimentation, however, has been carried on at a speed of twenty pictures per second. As shown in the drawings the gears 48 and 41 between the motor and main shaft of the machine are designed to give the equivalent speed of twenty pictures per second. If, however, these gears are removed and the motor lowered slightly and directly coupled to the main

shaft the speed will be at the rate of twenty-four pictures per second.

As the film passes out of the sound compartment through the opening 151 it winds on the winding wheel 235a which is permitted to slip 5 as has already been described as the diameter of the roll of film increases.

Where the machine is used in conjunction with other television scanning machines and the transmitted picture is observable on a monitor 10 receiving device it is highly desirable that a framing device be provided so that when the film scanner is started the framing of the picture may be adjusted to that of a picture previously sent out, or where sections of a film have been 15 joined incorrectly this may be compensated for by the picture framing device. Accordingly, the operator has only to swing the lever 198 downwardly or upwardly to move in the same direction the entire strip of film which is passing slot 11 longitudinally of the film, and the amount of throw is made sufficient so that the picture may be properly framed regardless of its position. The loop 202 at the top of the film permits this 20 movement of film without causing any change 25 in the speed at which the film is passing through the machine or without affecting in any way the operation of the driving sprockets.

The above mechanism will adequately take 30 care of framing the picture in a vertical direction. Framing the picture horizontally is usually accomplished both in a transmitter and receiver by rotating the entire motor and thus changing the position of the scanning element 35 horizontally with respect to the object field of the scanning apparatus. In the present machine rotating the entire motor would also change for an instant the speed of the sound mechanism with resultant distortions of the sound reproduction. I may find it preferable, therefore, to 40 eliminate the horizontal framing entirely.

However, one form of mechanism for accomplishing this purpose without interfering with the sound is shown in Fig. 19. In this figure the shaft 55 is shown provided with a slightly longer 45 spiral gear 300 which meshes with the gear 48 on the shaft 43. The gear 300 has a grooved hub 301 and is splined to the shaft 55 so that the two must rotate together. Movement of the gear 300 along the shaft 55 will cause it to alter its 50 point of contact with the gear 48 and as the gears are spiral gears the relative rotational position of the gear 300 with respect to the gear 48 will change. This change in the rotational position of the gear 300 will cause a corresponding 55 change in the rotational position of the mirror wheel at the upper end of the shaft and a corresponding change in the position of the mirrors with respect to the picture lines on the film.

In order to cause this shifting of the gear 300 60 along the shaft 55 I provide a bracket 302 having a bifurcated end 303 to engage the groove on the hub 301 of the gear. The bracket is slidably mounted in a suitable groove 303 in the wall of the casting member 24. A lug 304 on the bracket 65 extends through an opening 305 in the casting wall, and a tapped hole in the end thereof is engaged by a screw 306 rotatably mounted against longitudinal movement in a lug 307 formed on the outside of the casting. A knurled knob 308 70 on the end of the screw 306 permits its manual rotation and causes the entire bracket 302 to slide vertically in the grooves 303.

In framing the picture horizontally therefore the operator has only to rotate knob 308 where- 75

upon the mirror wheel will change its relative position without interfering in any way with the speed of the motor or the movement of the film through the machine.

5 The light cell 17 is preferably mounted in a vertical position with the lens 15 converging the light upon the light-sensitive element thereof. Fig. 16, however, shows a modified arrangement in which the light cell 17 is positioned horizontally and the lens 15 omitted. The cell is positioned as close as possible to the mirror wheel and in such a manner that the light from one of the mirrors as it enters the beam of parallel rays will project light upon one end of the cell and 10 then the light will sweep along the cell towards the other end as the mirror moves across the beam. The arrangement shown in the prior figures may be preferred because it appears to be difficult to obtain a light cell with uniform 15 response throughout the length of the light-sensitive element.

While it may be desirable to project the light from inside of the machine to a light-sensitive cell mounted on the outside the reverse can also 20 be done. In Fig. 17 an arrangement is shown diagrammatically where a light-sensitive cell 309 is positioned within the machine adjacent the slot 11 and preferably a cylindrical lens 310 is provided for diverging any light passing through 25 the slot 11 upon the cell 309. The mirror wheel 14 similar to that already described in connection with the other figures is positioned similarly with respect to the slot 11 and intercepts parallel rays 311 produced by a suitable optical system 312 similar to that described in connection with 30 the scanning apparatus. The mirrors on the mirror wheel pick up the parallel rays and redirect them through the slot 11 and film 10, which is being drawn past it, and on to the cell 309.

40 Fig. 18 shows still another arrangement for operating the mirror wheel without the use of parallel rays. Here a large amount of light is thrown against the film 10 by any suitable lighting arrangement and in front of the slot 11 is positioned an optical system 313 which projects a virtual image 314 of the slot and its light values onto a plane along which the edges of the mirror wheel 14 pass. The portion of the projected image falling upon one of the mirrors is projected through the lens 15 to the cell 17. Thus 45 the cell 17 can only receive light from the mirrors as they pass along the image plane.

As has been mentioned before it is necessary to move the film through the machine at a very 50 constant speed in order to get good sound reproduction and pictures without distortion. To insure the latter it is also necessary to rotate the mirror wheel at a constant speed as possible. In some instances it may be preferred to eliminate the gearing in the machine by using an 55 independent drive for each driving part of the machine. Thus in Fig. 20 the upper film sprocket 315 may be driven by a separate motor 316 upon whose shaft the sprocket 315 is preferably 60 mounted. The lower driving sprocket 317 may also be driven by a second motor 318, while the mirror wheel 319 may be driven by a motor 320. The motors 316, 318, and 320 are preferably synchronous motors so that they will run at exactly 65 the right speed and should be electrically connected to operate simultaneously so that the film driving sprockets will start and stop together.

If desired the entire motor 320 may be bodily rotated to frame the picture horizontally. One 70 way of accomplishing this is to provide a bracket

75 321 in which is mounted a short shaft 322 carrying a worm wheel 323 on one end and a rubber tired wheel 324 on the other. The motor 320 is mounted in a sleeve 325 and is rotatable therein and the bracket 321 is mounted on the sleeve. The wheel 324 bears against the motor 320 through a slot 326. A worm 327 meshing with the wheel 323 is mounted on a shaft 328 which is mounted in the bracket 321 and is provided with a knurled hand wheel 329 for rotating the 10 shaft. The motor may be thus completely rotated and the picture framed.

15 From the above description it will be evident that I have provided a film scanning machine which is adapted to pick up both the picture and sound from a standard motion picture film equipped with a sound track and which is simple to manufacture and assemble and which will operate with a high degree of efficiency and lends itself to easy handling.

20 Many changes may be made in the construction of the apparatus without departing from the spirit of the invention and I do not therefore desire to limit myself to what has been shown and described except as such limitations 25 occur in the appended claims.

25 What I claim is:

30 1. In a motion picture television transmitting apparatus a picture scanning device comprising a light source, a masking plate having a thin slot transverse to the film, means to project light from said source through said film and said slot, a light sensitive cell, means to reflect the light passing through individual portions of said slot successively upon said light-sensitive cell, means to guide the film past said masking slot, a sound reproducing device comprising means to direct a beam of light in a thin line through the sound track on said film, and a light-sensitive cell 35 adapted to receive the light passing through said sound track, means to guide the film through said sound reproducing device, single means to draw said film at a constant speed through said apparatus, and means positioned between the slot in said masking plate and said sound reproducing device and operable while said machine is in operation for adjusting the relative longitudinal position of said film with respect to said masking plate without disturbing the motion of the film past said sound reproducing device. 40

45 2. In a motion picture film scanning device a light source, means to direct light from said source through a thin transverse line of said film, a light-sensitive cell on the opposite side of said film, a scanning element between said film and said light-sensitive cell, means to draw said film at a constant speed through said device, means to rotate said scanning element at a speed determined by the speed of the film through said device, means to alter the relative position of said scanning element while the machine is in operation, means to adjust the relative position of said film with respect to the light passing therethrough.

50 3. In a motion picture film television transmitting apparatus the combination of a scanning device comprising means to scan the picture portion of the film in successive lines, means to translate said scanned lines into electrical impulses, means to translate the sound track on said film into electrical impulses, means to draw said film at a constant speed through said apparatus, means to adjust the relative position of said film with respect to said picture scanning means, means to drive said picture scanning 55 60 65 70 75 80 85 90 95 100 105 110 115 120 125 130 135 140 145 150 155 160 165 means at a speed determined by the speed of the film through said apparatus, and means to adjust the relative position of said film scanning device with respect to said film while said apparatus is in operation.

5. 4. A scanning element for a television transmitter comprising a wheel, a plurality of mirrors positioned on the periphery of said wheel and spaced from each other a distance a little less than the width of the picture to be scanned, and single means to anchor said mirrors in position on said wheel, said means comprising a removable ring in engagement with all of said mirrors.

5. 5. A scanning element for a television transmitter comprising a wheel, a rim on said wheel, a plurality of transverse slots in said rim, a mirror positioned in each of said slots, and a ring engaging said mirrors and attached to said rim to lock said mirrors in said slots.

20. 6. A scanning element for a television transmitter comprising a wheel, a rim around the periphery of said wheel, a groove in said rim, a plurality of transverse slots formed in said rim and spaced from each other at equal distances around the circumference thereof, a plurality of plates, one positioned in each of said slots, a mirrored surface on the outer end of each of said plates, each of said plates having a central portion of reduced cross-section equal in length to the width of said groove, a ring adapted to fit into said groove and hold said plates in position in said slots, and means to rigidly secure said ring to said wheel.

7. 7. In a motion picture film television transmitting apparatus, a driving sprocket for said film adapted to introduce the film into said machine, a second driving sprocket for said film adapted to draw said film through said machine and acting as the only drawing means therefor, means to control the rotation of said second sprocket so as to maintain the speed thereof at a very constant rate and prevent variations of the driving force from affecting the speed of the film, means to scan the film in transverse lines as it passes through said machine, means to translate a sound track on said film into a series of electrical impulses, said sound track translating means being adjacent to said second sprocket and there being a loop in said film between said picture scanning means and said first sprocket, and means to adjust the relative position of said film

with respect to said picture scanning means without affecting the speed of said film passing said sound track translating means.

8. In a motion picture film television apparatus a picture scanning device, a sound reproducing device, single means to draw the film at a constant uniform speed past said devices, a roller over which said film passes in going from said picture scanning device to said sound translating device, and means to adjust the position of said roller so as to change the position of said film with respect to said picture scanning device without disturbing the speed of the film past said translating device.

9. In a motion picture film television transmitting apparatus the combination of a scanning device comprising means to scan the picture portion of the film in successive lines, means to translate said scanned lines into electrical impulses, means to translate the sound track of said film into electrical impulses, single rotatable means to draw said film through said apparatus, an inertia member rigidly attached to said last mentioned means and adapted to rotate with it, resilient means to drive said inertia member at a substantially constant speed, means adjacent said sound translating means to retard the free movement of said film, and means to adjust the relative position of said film scanning device with respect to said film while said apparatus is in operation.

10. In a motion picture film television transmitting apparatus the combination of a scanning device comprising means to scan the picture portion of the film in successive lines, means to translate said scanned lines into electrical impulses, means to translate the sound track of said film into electrical impulses, single rotatable means to draw said film through said apparatus, an inertia member rigidly attached to said last mentioned means and adapted to rotate with it, resilient means to drive said inertia member at a substantially constant speed, means adjacent said sound translating means to retard the free movement of said film, means to adjust the relative position of said film with respect to said picture scanning means, and means to adjust the relative position of said film scanning device with respect to said film while said apparatus is in operation.

ARNO ZILLGER. 50
